MAGAZINE FOR FIREARMS

Oertel F. Van Horn, New York, and John D. Whittaker, Babylon, N. Y., assignors to Automatic Appliance Corporation, New York, N. Y., a corporation of New Jersey

Application March 3, 1941, Serial No. 381,452

4 Claims. (Cl. 42—50)

This invention relates to a magazine unit for fire-arms and refers more particularly to a container for cartridges which is adapted to be attached to fire-arm and which supplies cartridges automatically, one after the other, to the firing chamber of the fire-arm.

In our co-pending application for United States Letters Patent, filed Feb. 21, 1941, Ser. No. 379,916 and relating to "Firearms," we have described pistols and rifles which may be converted by a selector mechanism into continuously shooting guns discharging bullets automatically, one after the other, while the shooter holds the trigger in a depressed position. These fire-arms may also be used for the usual intermittent shooting in the course of which the trigger must be pulled and released once for each shot.

These and similar rifles and pistols are usually provided with fire-arm magazines which are adapted to contain a limited number of bullets, usually seven, and which are inserted into the hollow handle of a pistol or are attached to the casing of a rifle.

While this small supply of cartridges often suffices for intermittent shooting, the fire-arm must be supplied automatically with a much larger number of cartridges if it is to fulfill the purpose of a machine gun during continuous firing.

An object of the present invention is to provide a magazine unit containing a large number of cartridges, say, twenty five, thirty or forty cartridges, and having means automatically supplying these cartridges, one after the other, to the chamber of a fire-arm.

Another object is the provision of a magazine for cartridges which is comparatively small in size and light in weight and which is provided with simple, sturdy and effectively operating means withdrawing the cartridges automatically one after the other from the magazine and supplying them to the chamber of an automatically firing fire-arm.

A further object is to combine the fire-arm magazine of pistols and rifles which contains a small number of cartridges, with a second cartridge magazine holding a much larger number of cartridges, and cooperating with the fire-arm magazine in such manner that the cartridges may be supplied in a continuous flow from the cartridge magazine into the fire-arm magazine and thence into the chamber of the fire-arm.

A still further object of the present invention is the provision of a magazine for cartridges which is provided with an adjustable cartridge-

releasing mechanism and which is so constructed that incorrect loading can be immediately detected.

Yet another object is the provision of a magazine unit including a cartridge magazine and a fire-arm magazine, and provided with two separate spring-actuated cartridge-releasing devices operating automatically, one after the other, to withdraw cartridges from the magazines and to supply them successively to the chamber of the fire-arm.

Other objects will become apparent in the course of the following specification.

In accomplishing the above and other objects of the present invention, it was found advisable to provide a magazine unit including a cartridge magazine having a spring-actuated cylinder or drum situated within a casing and carrying partitions upon its periphery to provide a plurality of cartridge-containing chambers.

The casing is provided with an opening through which the cartridges in these chambers may be ejected one after the other by the rotation of the drum.

25 A fire-arm magazine of the type having a follower actuated by a spring, is mounted upon the casing over this opening. The drum is provided with an inner pocket or chamber which is situated opposite the opening in the unloaded position of the drum and which received the spring of the fire-arm magazine.

The follower of the fire-arm magazine is so shaped that it may be clamped within the pocket and close to the periphery of the drum by a clamping mechanism carried by the drum, while the chambers of the drum are being loaded, or while cartridges from these chambers are being discharged.

An automatically operable releasing mechanism is used to enable the follower and the adjacent end of the follower spring to move into the fire-arm magazine whenever this is necessary to unload the cartridges in the fire-arm magazine.

The invention will appear more clearly from the following detailed description when taken in connection with the accompanying drawings showing, by way of example, preferred embodiments of the invention idea.

In the drawings:

50 Figure 1 is a perspective view illustrating a magazine unit constructed in accordance with the principles of the present invention.

Figure 2 is a side view, partly in section, illustrating a pistol with a magazine unit attached thereto in the firing position.

Figure 3 is a fragmentary section along the line 3—3 of Figure 2.

Figure 4 is a longitudinal section through the magazine unit.

Figure 5 is a section along the lines 5—5 of Figure 4.

Figure 6 shows the cartridge magazine with its cover removed, in side elevation, partly in section, during loading or firing.

Figure 7 is similar to Figure 6 and shows the cartridge magazine when it is fully loaded.

Figure 8 is a fragmentary rear view of the cartridge magazine in its unloaded position.

Figure 9 is a fragmentary inner view of the cover of the cartridge magazine.

Figure 10 shows the cartridge magazine in side elevation, partly in section, in the position in which the last cartridges are being unloaded from the cartridge magazine.

Figure 11 is similar to Figure 10 and shows the parts in an unloading position in which the last cartridge has been removed from the cartridge magazine into the fire-arm magazine.

Figure 12 is a fragmentary section along the line 12—12 of Figure 10.

Figure 13 is a fragmentary section along the line 13—13 of Figure 11.

Figures 14 and 15 are similar to Figure 5 and illustrate the movement of the cartridges from the cartridge magazine to the fire-arm magazine.

The magazine unit shown in the drawings includes a cartridge magazine 20 connected with the fire-arm magazine 21.

When the magazine unit is not being used, the upper end of the casing 19 of the fire-arm magazine 21 may be closed by a correspondingly shaped cover 27, shown in Figure 1.

The fire-arm magazine 21 is provided with the spring 62 (Fig. 4) actuating a follower 75 having a cartridge-supporting surface 76 and two grooves 77 and 78 formed upon the side surfaces of the follower and used for clamping the follower, as will be described in detail hereinafter.

In order to attach the loaded magazine unit to a fire-arm, the cover 27 is removed and the magazine 21 is inserted into the hollow handle 30 of a pistol 31, as shown in Figure 2.

The upper open end of the casing 19 of the fire-arm magazine 21 is provided with inwardly bent edges for maintaining in position the uppermost cartridge 57. The usual slot 32 of the casing 19 receives the projection 33 of a magazine catch 34 loaded by a spring 35. As shown in Figure 3, the magazine 21 is firmly held by the magazine catch 34 within the handle 30.

The casing 19 has a lower portion 22 of greater thickness and the lower edges of the handle 30 rest upon the shoulders of the portion 22.

The portion 22 has two parallel flanges 23 (Fig. 4) which fit into grooves 24 provided in a bead 25 enclosing the discharge opening 26 of the cartridge magazine 20, and constituting a part of the casing 36 of the cartridge magazine.

A downwardly extending lip 28 of the casing 19 engages an inner surface of the cover 29 of the cartridge magazine 20 (Fig. 5).

The casing 36 of the cartridge magazine 20 includes an annular portion 55 and a curved edge 71. The casing carries a shaft 37 which is integral with a ratchet gear 38 and which has an end portion 39 projecting out of the casing 36 and carrying a knob 40 which is firmly connected to the shaft end 39 by a screw 41.

The casing 36 carries a pawl 68 (Fig. 8) which is in engagement with the ratchet gear 38 and

which is pressed against its teeth by a spring 69.

Another threaded end 42 of the shaft 37 is of smaller diameter and carries a knob 43 (Fig. 5). The knob 43 which is screwed upon the shaft end 42, may be unscrewed when removing the cover 29.

One end 44 of the spirally wound leaf spring 45 is riveted or otherwise firmly connected to the shaft 37. The opposite end of the spiral spring 45 has the form of a sleeve 46 enclosing a pin 47 which is carried by a drum or cylinder 49 within the hollow interior 48 thereof.

The drum or cartridge carrier 49 consists of two parallel discs 50 and 51 which are mounted upon the shaft 37 and which are interconnected by a rim 52.

The outer surfaces of the rim 52 carry radially extending projections 53 which are separated by substantially cylindrical grooves 54, the diameter of which corresponds to that of a cartridge shell, so that the space between the drum 49 and the adjacent annular wall 55 of the casing 36 is divided into a plurality of chambers 56, each of which may contain a cartridge 57.

The drum 49 is held in the unloaded position shown in Figures 4 and 5, against the pressure of the spring 45 by the engagement of a projection 58 carried by the disc 50 of the drum 49 with a stop 59 which is carried by or integral with the casing 36.

The drum 49 may be locked and released from the outside by a locking device which is shown in greater detail in Figure 13 and which includes a knob 103 mounted upon an outer surface of the casing 36 by means of a pin 104 extending through the casing and connected with a lock 105 which is located within the casing and which fits into a recess 110 provided in the drum 49. A spring 111 engaging the lock 105 serves to maintain the lock in its locking or open positions.

In the position shown in Figure 4, the opening 26 of the cartridge magazine is separated from one of the chambers 56 by a transversely extending wall 60 having a rounded peripheral surface 61 corresponding in form to the annular wall 55 of the casing 36. An inclined cartridge-receiving and cartridge-raising plate 82 provided with a large central opening 81 is situated on the other side of the opening 26 and is carried by the casing 36.

The drum includes a transverse chamber or pocket 80 which is enclosed on two sides by the rim 52 and an inner wall 63, and on the other two sides by the discs 50 and 51 of the drum 49.

The disc 51 of the drum 49 carries a plurality of peripherally disposed teeth 64 which mesh with a pinion 65 keyed upon a shaft 66 mounted in the cover 29.

The shaft 66 is firmly connected with a winged nut 67 situated outside of the cover 29 and used to rotate the drum 49 and wind the spring 45 while the magazine unit is being loaded.

The cover 29 carries an annular rib or flange 70 (Fig. 5) extending close to the chambers 56 and serving as a guide for the cartridges 57 situated within these chambers. Flanges 70 of different heights may be used to guide cartridges of different calibers, however, a different casing 19 must be used for each caliber. As shown in Figure 5, the curved portion 71 of the casing 36 corresponds substantially to the curvature of the bullets 72 of the cartridges 57. Due to the provision of the flange 70, the cartridges 57 fit

into the chambers 56 only when they are properly inserted into the magazine unit.

The clamping device which is used for holding the follower 75 within the pocket 80, includes two pawls 85 and 86 (Fig. 4) provided with reduced ends for engaging the grooves 77 and 78, respectively, of the follower.

The pawl 85 which is situated in a recess 88, is keyed upon a shaft 87 mounted in the wall 60. The pawl 86 is situated in a recess 90 and is keyed upon a shaft 89 which is mounted in the wall 63.

As shown in Figures 6, 7, 10, and 11, the shaft 87 carrying the pawl 85 is firmly connected with a link 91, one end of which carries a pin movable within a slot 92 of a lever 93. The shaft 89 carrying the pawl 86 is connected in a similar manner with a link 94 having a pin which is movable in another slot 95 provided in the lever 93.

The lever 93 has a round portion 96 which is mounted upon a corresponding portion of the shaft 37.

The disc 51 of the drum 49 carries a stop 97 for the lever 93 and the lever 93 is pressed against this stop by a spring 98 having the form of a U, one of the legs of which is attached to the lever 93 by being inserted into an opening formed therein. The other leg of the spring 98 is held in an opening provided in the disc 51.

The links 91 and 94 are arranged in such manner that when the lever 93 is pressed against the stop 97 by the spring 98, the pawls 85 and 86 project into the pocket 80 and may engage the grooves 77 and 78 of the follower 75. However, the links 91 and 94 will move along with the lever 93 when the latter is swung toward the spring 98, thereby compressing the spring, and then the shafts 87 and 89 will carry out a turning movement and withdraw the pawls 85 and 86 from the chamber 80, thereby releasing the follower 75.

The device used for actuating the lever 93 includes a spring 99 carried by the cover 29. As shown in Figures 9, 10 and 11, the leaf spring 99 is arcuate in form and has a bent end.

The spring 99 carries a projection 100 which is adapted to engage an upper edge of the lever 93 while the drum 49 is being rotated in the direction of the arrow 101 shown in Figure 10, to discharge the cartridges.

The drum 49 also carries a pin 102 which may be engaged by the bent end of the spring 99, thus bending the spring 99 outwardly and releasing the lever 93 from engagement with the projection 100.

It is apparent from the above that during the loading of the magazine unit the drum 49 must be turned and the spring 45 wound, while the spring 45 unwinds itself during the unloading. Whenever the tension of the spring 45 becomes too weak as a result of continuous use of the magazine unit, it may be conveniently increased by turning the knob 40 in the direction of the arrow 107 shown in Figure 4. The shaft 37, the pinion 38 and the adjacent end 44 of the spring 45 will turn together with the knob 40. The pawl 63 engaging the pinion 38 will prevent the turning of the shaft 37 in the opposite direction.

It is possible to load the magazine unit by removing the cover 29 of the cartridge magazine 20 and then inserting the cartridges sidewise into the chambers 56, the drum 49 being rotated and the spring 45 tensioned independently of the insertion of the cartridges.

However, the more customary procedure is to load the magazine unit by inserting the cartridges one by one into the upper open end of the fire-arm magazine 21, while the drum is turned stepwise in the direction of the arrow 107 by means of the winged nut 67.

Figures 4 and 5 illustrate the magazine unit at the beginning of the loading operation, although, obviously, the various parts of the magazine unit 10 will have the same positions close to the end of the unloading operation.

In the position shown in Figures 4 and 5, the drum 49 is held against the action of the spring 45 by the engagement of the projection 58 with the stop 59. In this unloaded position of the drum 49 the opening 26 of the magazine 20 is situated opposite the outer end of the pocket 80. The follower spring 62 is located in the bottom of the pocket 80 and the outer end of the pocket 20 80 is closed by the follower 75 which is held in place by the engagement of the pawls 85 and 86 with its grooves 77 and 78, respectively. The cartridges fill the fire-arm magazine 21 and the lower-most cartridge rests within the opening 26 upon the cartridge supporting surface 76 of the follower 75.

Then the user turns the winged nut 67 step by step while continuing to feed the cartridges through the upper end of the fire-arm magazine 36 21. Since the nut 67 is firmly connected with the pinion 65 meshing with the teeth 64 of the drum 49, the drum 49 will be rotated step by step against the action of the spring 45.

In the course of this rotation of the drum 49, 35 the cartridge resting upon the surface 76 of the follower 75 will be moved away from the opening 26 in the direction of the arrow 107 and a projection 53 will move through the central opening 81 of the inclined cartridge-supporting plate 40 82. Then the next cartridge will drop into position upon the drum 49, as shown in Figure 6.

The cartridges will fall one after the other into the chambers 56, as these chambers are moved below the opening 26 in the course of the 45 rotation of the drum 49.

As shown in Figure 7, the cartridge magazine 20 is fully loaded when all the chambers 56 are filled with cartridges which also fill the fire-arm magazine 21.

As already stated, the loaded magazine unit is inserted into the pistol 31 in the manner indicated in Figure 2. The cartridges are supplied one after the other from the upper end of the fire-arm magazine 21 to the chamber of the pistol by the reciprocation of the slide of the fire-arm 55 in the usual manner which is not illustrated.

As the cartridges are being removed from the upper end of the fire-arm magazine, the spring 45 will turn the drum 49 in the direction of the arrow 101 (Fig. 10). A cartridge situated within the opening 26 close to the support 82 will be raised from its chamber 56 into the fire-arm magazine 21 by the pressure of a projection 53 directed toward the support 82. This upward movement of a cartridge from the opening 26 of the cartridge magazine 20 into the lower end of the fire-arm magazine 21, will shift upwardly all the cartridges situated within the magazine 21, so that the uppermost cartridge will be placed within the path of movement of the fire-arm slide. The cartridges serve as bearings turning about their axes while the drum 49 is being rotated.

The lever 93 moves along with the drum 49 75 and is pressed against the stop 97 by the spring

98 while the drum is turned by the spring 45 from the position shown in Figure 7 to the position shown in Figure 10.

However, as illustrated in Figure 10, the upper end of lever 93 strikes against the projection 100 carried by the spring 99 during the unloading operation at a time when two last cartridges remain in the cartridge magazine 20. The projection 100 will then maintain the lever 93 in the position shown in Figure 10, while the drum 49 continues to move in the direction of the arrow 101. One more cartridge will be pushed upwardly into the lower end of the fire-arm magazine 21 by the pressure of the adjacent last cartridge, which is directed toward the plate 82. At 15 the same time, the movement of the pawl-carrying shafts 87 and 89 which are mounted in the drum 49, relatively to the lever 93 will swing the links 91 and 94 and thus turn the shafts 87 and 89 along with their pawls 85 and 86. The pawls 20 25 and 86 will move out of the grooves 77 and 78 of the follower 75, thereby releasing the follower which will be moved slightly upward to clear the pawls 85 and 86 by its spring 62. This movement is made possible by the play between 25 the cartridges in the magazine 21. When the next cartridge is fired, the last cartridge situated within the cartridge magazine 20 and carried by the supporting surface 76 of the follower 75, will be raised into the lower end of the fire-arm magazine 21, by the spring 62, as indicated in Figure 11.

While the drum 49 moves from the position shown in Figure 10 to the position shown in Figure 11, the pin 102 carried by the drum 49 strikes the bend end of the immovable spring 99 and pushes this spring outwardly, thereby withdrawing the projection 100 from engagement with the lever 93. The spring 98 will then move the lever 93 back into its original position in which the lever 93 is pressed against the stop 97 and the ends of 30 the pawls 85 and 86 project into the chamber 80 and are ready to grasp the follower 75. However, at that time the follower 75 is situated within the fire-arm magazine 21 and is pressed upwardly by the spring 62 which is sufficiently narrow so as 35 not to be engaged by the pawls. The upward movement of the cartridges in the fire-arm magazine 21 during firing is now caused by the follower 75 actuated by its spring 62. This upward movement continues until the last cartridge carried by the surface 76 of the follower 75 is moved to the upper end of the fire-arm magazine 21 and is ready to be supplied to the chamber of the fire-arm. After the firing of that cartridge it is replaced by the follower 75 which is now situated in its uppermost position, while the spring 62 occupies substantially all of the interior of the fire-arm magazine 21.

At the beginning of the reloading operation, the cartridges are inserted one after the other into the fire-arm magazine 21 through its open upper end; they push downward the follower 75 and compress the spring 62 until the entire fire-arm magazine 21 is filled with cartridges and the follower 75 is pushed into the pocket 80. The lower surfaces of the follower 75 are so shaped that they will move below the pawls 85 and 86 and will enable the pawls to spring into the grooves 77 and 78, thereby locking the follower 75 in the position shown in Figure 4.

It is apparent that the specific illustrations shown above have been given by way of illustration and not by way of limitation and that the structures above described are subject to wide variation and modification without departing

from the scope or intent of the invention, all of which variations and modifications are to be included within the scope of the present invention.

What is claimed is:

1. A magazine unit for cartridges, comprising in combination with a fire-arm magazine having a casing, a follower and a spring engaging said follower for moving the same; a cartridge magazine having a casing detachably connected with the casing of the fire-arm magazine and communicating therewith, a drum situated within the casing of the cartridge magazine and having a plurality of cartridge-containing chambers, said drum having an inner pocket formed therein and situated close to said fire-arm magazine in the unloaded position of the drum, a spring for actuating said drum, a projection carried by said drum, a stop carried by said casing and engaged by said projection in the unloaded position of said drum, said drum having a plurality of peripheral teeth formed thereon, a pinion meshing with said teeth, a shaft extending through the casing of the cartridge magazine and carrying said pinion, whereby the drum-actuating spring may be wound by turning said drum from said unloaded position to a loaded position, said chambers of the drum supplying cartridges successively toward the casing of the fire-arm magazine when the drum is turned by the unwinding of the drum-actuating spring from said loaded position to said unloaded position, means carried by said drum for locking said follower and said spring within said pocket during at least a part of the rotation of said drum, and means situated within and carried by the casing of the cartridge magazine for actuating said locking means to release said follower when said follower is close to the casing of the fire-arm magazine to enable said follower-actuating spring to move said follower into the casing of the fire-arm magazine.

2. A magazine unit for cartridges, comprising in combination with a fire-arm magazine having a casing, a follower and a spring engaging said follower for moving the same; a cartridge magazine having a casing connected with the casing of the fire-arm magazine and communicating therewith, a drum situated within the casing of the cartridge magazine and rotatable from an unloaded position to a loaded position, a spring for rotating said drum from said loaded position to said unloaded position, said drum having cartridge-supporting grooves and an inner pocket formed in said drum and situated close to said fire-arm magazine in the unloaded position of said drum, said cartridge-supporting grooves of the drum supplying cartridges successively toward the casing of the fire-arm magazine when the drum is rotated from said loaded position to said unloaded position, two shafts carried by said drum on opposite sides of said pocket, pawls rotatable along with said shafts and having ends adapted to project into said pocket to lock said follower therein, said follower-actuating spring being situated within said pocket between the bottom thereof and said follower when said follower is locked by said pawls, links having ends firmly connected with said shafts, a lever carried by said drum and movable from a locked position to an open position and vice versa, said lever having slots formed therein, said links having other ends mounted in said slots, said slots being so disposed that the ends of the pawls project into said pocket when said lever is in its locked position, a stop carried by said drum and engaging said lever when it is in its locked position, a spring

having an end engaging said drum and another end engaging said lever for pressing said lever against said stop, whereby said lever is maintained in its locked position during at least a part of the rotation of said drum, and means situated within and carried by the casing of the cartridge magazine for moving said lever into said open position when said pocket is close to the casing of the fire-arm magazine to enable said follower-actuating spring to move said follower into the casing of the fire-arm magazine.

3. A magazine unit for cartridges, comprising in combination with a fire-arm magazine having a casing, a follower and a spring engaging said follower for moving the same; a cartridge magazine having a casing connected with the casing of the fire-arm magazine and communicating therewith, a drum situated within the casing of the cartridge magazine and rotatable from an unloaded position to a loaded position, a spring for rotating said drum from said loaded position to said unloaded position, said drum having cartridge-supporting means and an inner pocket formed in said drum and situated close to said fire-arm magazine in the unloaded position of said drum, said cartridge-supporting means of the drum supplying cartridges successively toward the casing of the fire-arm magazine when the drum is rotated from said loaded position to said unloaded position, two pawls rotatably mounted in said drum on opposite sides of said pocket and having ends adapted to project into said pocket to lock said follower therein, said follower-actuating spring being situated within said pocket between the bottom thereof and said follower when said follower is locked by said pawls, a lever carried by said drum and movable from a locked position to an open position and vice versa, means for operatively connecting said pawls with lever, whereby the ends of the pawls project into said pocket when said lever is in its locked position, means for maintaining said lever in its locked position during at least a part of the rotation of said drum, a spring carried by the casing of the cartridge magazine, a projection carried by said spring and engaging said lever when said pocket is close to the casing of the fire-arm magazine to cause a movement of said lever into its open position, whereby said follower is released by said pawls to enable said follower-actuating spring to move said follower into the casing of the fire-arm

magazine, and a stop carried by said drum and engaging the last-mentioned spring after said follower is released to withdraw said projection from engagement with said lever and thereby cause a return of said lever into its locked position.

4. In a magazine unit, a cartridge magazine comprising a substantially cylindrical casing having a peripheral opening formed therein for the removal of cartridges, a removable cover for covering said casing, an inclined cartridge-raising plate carried by said casing and situated within said casing adjacent to said opening, a shaft mounted in said casing and said cover, a hollow drum carried by said shaft and having a plurality of radial cartridge-supporting projections spaced from said casing and cartridge-containing grooves formed upon said drum between said projections, a portion of the casing of the cartridge magazine being curved in conformity with an outline of the forward end of a cartridge, a spiral spring situated within said drum and having one end connected to said shaft and another end connected to said drum, a pinion rotatable along with said shaft, a pawl meshing with said pinion, a spring pressing said pawl against said pinion, a knob firmly connected with an end of said shaft and situated outside of said casing, whereby the tension of said spiral spring may be adjusted by turning said knob, another knob removably mounted upon the other end of said shaft and situated outside of said cover, a rib carried by said cover for engaging the cartridges in said grooves, a projection carried by said drum, a stop carried by said casing and engaged by said projection in an unloaded position of said drum, said drum having a plurality of peripheral teeth formed thereon, a pinion meshing with said teeth, and a shaft extending through the casing of the cartridge magazine and carrying the last-mentioned pinion, whereby said spiral spring may be wound by turning said drum from said unloaded position to a loaded position, said projections of the drum supplying cartridges successively toward said opening and said cartridge-raising plate when the drum is turned by the unwinding of said spiral spring from said loaded position to said unloaded position.
